Attorney

UNITED STATES PATENT OFFICE.

CHARLES RAMSTEAD, OF OKMULGEE, OKLAHOMA.

BOILER.

Application filed May 9, 1922. Serial No. 559,663.

To all whom it may concern:

Be it known that I, CHARLES RAMSTEAD, a citizen of the United States, residing at Okmulgee, in the county of Okmulgee and State of Oklahoma, have invented a new and useful Boiler, of which the following is a specification.

By way of explanation it may be stated that a known form of domestic boiler comprises a shell and a central flue. When it is desired to mount a known form of thermostat in the boiler, considerable difficulty has been experienced hitherto by reason of the fact that the tube of the thermostat encounters the central flue of the boiler. In view of the foregoing, this invention aims to provide novel means for mounting a thermostat tube in the shell of a boiler in such a way that the tube will clear the central flue of the boiler.

In the accompanying drawings:—

Figure 1 shows in horizontal section, a portion of a boiler wherein the device forming the subject matter of this application has been mounted; and Figure 2 is a section on the line 2—2 of Figure 1.

In Figure 1 there is shown a boiler comprising a shell 1 and a central flue 2. A thimble 3 may be mounted in the shell 1. A coupling of tubular form is supplied, the coupling comprising an inner member 4 and an outer member 5, the members 4 and 5 preferably being formed integrally and being disposed at an obtuse angle to each other. The inner member 4 of the coupling is externally threaded as at 6, for engagement with the thimble 3. In the inner end

of the member 4 a notch or seat 7 is fashioned. At its outer end, the member 5 is internally threaded as at 8 to cooperate with the enlarged portion 9 of a thermostatic tube 10, the tube 10 extending into the shell 1 of the boiler and passing through the notch or seat 7 in the member 4 of the coupling.

The construction, obviously, is such that the thermostatic tube 10 may be so mounted in the boiler as to clear the flue 2 as depicted in Figure 1.

What is claimed is:—

In a device of the class described, a boiler comprising a shell and a central flue, a thimble mounted in the shell and disposed radially of the shell and the flue; a coupling of tubular form, comprising an inner member and an outer member disposed at an obtuse angle to each other, there being a notch in the inner end of the inner member, the inner member being threaded into the thimble and being disposed radially of the shell and the flue, and the outer member being disposed externally of the thimble; and a thermostatic element threaded into the outer member of the coupling and extended through the notch in the inner member of the coupling, the thermostatic element being extended to one side of the flue.

In testimony that I claim the foregoing as my own, I have hereto affixed my signature in the presence of two witnesses.

CHARLES RAMSTEAD.

Witnesses:

M. L. SUMNER,
ARTHUR VICTOR FREEDMAN.
